United States Patent Office

Des. 205,924
Patented Oct. 11, 1966

205,924

LIQUID DISPENSING UNIT

Peter A. Zelisko, Chicago, Ill., assignor to Home Tap Company, Chicago, Ill., a corporation of Illinois

Filed Dec. 6, 1965, Ser. No. 91

Term of patent 14 years

(Cl. D2—3)

FIG. 1 is an elevational view taken from one side of a liquid dispensing unit showing my new design;

FIG. 2 is a front elevational view thereof;

FIG. 3 is a top plan view thereof;

FIG. 4 is an elevational view taken from the side opposite that shown in FIG. 1;

FIG. 5 is a rear elevational view thereof; and

FIG. 6 is a bottom plan view thereof.

I claim:

The ornamental design for a liquid dispensing unit, substantially as shown.
